OLIVER J. HEATH, OF TOLEDO, OHIO, ASSIGNOR TO THE BUNTING BRASS & BRONZE COMPANY, OF TOLEDO, OHIO, A CORPORATION OF OHIO

GRAPHITING MACHINE

Application filed February 9, 1931. Serial No. 514,656.

This invention relates generally to machines for feeding graphite into bushings and consists of certain novel features of construction, combinations and arrangements of parts that will be hereinafter more fully described and particularly pointed out in the appended claims.

In the accompanying drawings:

Figure 1 is a side elevation of a machine embodying my invention and showing the graphite feeding piston in its uppermost position after the graphite cylinder has been emptied;

Figure 1A is a view similar to Figure 1 but showing a graphite feeding piston in lowermost position after the graphite cylinder has been filled with graphite;

Figure 2 is a rear elevation of the machine and showing a portion of the bushing on the arbor broken away;

Figure 3 is a detail view of the arbor;

Figure 4 is a sectional view through the arbor cap;

Figure 5 is a sectional view through the lower plug for the uppermost air cylinder;

Figure 6 is a sectional view through the upper plug for the uppermost air cylinder;

Figure 7 is a sectional view through the graphite cylinder;

Figure 8 is a sectional view through the lowermost air cylinder;

Figure 9 is a sectional view through the uppermost air cylinder;

Figure 10 is a sectional view through the double acting valve;

Referring now to the drawings, A is a supporting frame and B and C respectively are vertically spaced brackets projecting laterally from the frame at the upper end thereof. Preferably the frame A comprises two sections 1 and 2 respectively that are bolted together. As shown, the lower section 1 is substantially rectangular in form and has a flat base 3 that is adapted to be bolted to a suitable flooring or other support. The upper section 2 has a substantially horizontal portion 4 resting on the upper end of the lower section 1 and has a substantially vertical portion 5 rising from the horizontal portion 4 and provided adjacent its upper end with

laterally spaced elongated slots 6. The brackets B and C have substantially flat attaching portions 7 and 8 respectively bolted to the vertical portion 5 of the frame and have vertically aligned tubular portions 9 and 10 respectively. Preferably the bolts 11 used

to secure the upper bracket C to the frame are received in the elongated slot 6 so that the bracket C is adjustable vertically relative to the fixed lower bracket B. 12 is a cylinder for graphite supported in the bracket B and provided adjacent its upper end with an inlet 13 for graphite.

14 is a bushing arbor having a reduced portion 15 threaded in the upper end of the graphite cylinder 12 and having axial, transverse and annular grooves 16, 17 and 18 respectively adapted to receive graphite in the order named from the cylinder 12, and 19 is an air cylinder threaded onto the lower end of the graphite cylinder 12.

Preferably the cylinder 12 for graphite fits snugly in the tubular portion 9 of the lower bracket B and is provided at its upper end with a lateral flange 20 that rests upon the upper end of said tubular portion. The arbor 14 is provided at its lower end just above the reduced portion 15 with an annular flange 21 that constitutes a seat for the work such as a bushing 22, and the air cylinder 19 is inverted

cup-shape in form and is closed at its lower end by a plate 24 provided axially with a suitable air inlet 25. D and E respectively are reciprocating pistons within the cylinders 19 and 12, and 26 is a rod movable axially of the cylinders and terminally connected to the pistons so that they will operate in unison.

Preferably the piston D comprises a leather cup 27 reinforced by suitable metal plates or discs 28 and 29, while the piston E comprises a leather cup 30 reinforced by metal discs 31 and 32 respectively. As shown, these pistons are sleeved upon opposite ends of the rod 26 against shoulders thereof and are held thereon by nuts 33 and 34 respectively. 35 is a valve of the single acting type for controlling

the supply of air through suitable tubing 36 to the air inlet 25 in the cylinder 19, and 37 is a pedal for operating said valve. As shown, this valve is conventional in design and includes a rocker 38 that is connected to

the pedal 37 by a long link 39. Preferably a coil spring 40 is terminally secured to the link 39 and to the section 1 of the frame and is adapted to return the rocker 38 and link 39 to normal position after they have been actuated by the pedal, as will be hereinafter more fully described. 41 is an air cylinder supported in the upper bracket C in substantially vertical alignment with the graphite cylinder 12; 42 is a plug threaded in the upper end of said air cylinder and having an axial air inlet 43, and 44 is a plug threaded in the lower end of said air cylinder and having a substantially L-shaped air inlet 45. Preferably the cylinder 41 fits snugly in the tubular portion 10 of the bracket C and is provided at its lower end with a lateral flange 48 that engages the lower end of the tubular portion 10. A nut 49 is threaded on the cylinder 41 intermediate its ends and engages the upper end of the tubular portion 10. Thus between the flange 48 and nut 49 a cylinder 41 is securely held in place in the bracket C. F is a reciprocating piston within the cylinder 41; 50 is a rod secured to the piston and movable axially of the cylinder and plug 44; 52 is a nut threaded in the plug 44 and constituting a guide for the rod 50; and 53 is a cap threaded onto the lower end of the rod 50 and adapted to clamp a bushing such as 22 upon the arbor 14 while graphite is being fed thereto from the cylinder 12. Preferably the piston F comprises two leather cups 54 and 55 separated by a metal spacer 56 and reinforced by metal discs 57 and 58 respectively and is secured by a nut 59 against a shoulder of the rod 50. The cap 53 is inverted cup-shape in form and has a vent 60 in one side thereof to permit the escape of air when the graphite is forced into the bushing 22 from the annular passage 18 in the arbor. 61 is a valve of the double acting type for controlling the supply of air through suitable tubing 62 and 63 respectively to the inlets 43 and 45 respectively; and 64 is a pedal for operating the valve 61. As shown, the valve 61 is of conventional design and includes a rocker 65 that is connected to the pedal 64 by means of a long link 66. A coil spring 67 is terminally secured to said link 66 and to the lower section 1 of the frame and is adapted to return the rocker 65 and link 66 to normal position after the pedal 64 has been released.

In use any suitable means such as a graphite gun (not shown) may be applied to the inlet 13 to supply graphite to the cylinder 12. Assuming the parts to be in the position illustrated in Figure 1, the graphite supplied to the cylinder 12 through the inlet will press down upon the piston F and will cause said piston and the rod 26 and piston D to be lowered to the position illustrated in Figure 1A. After a bushing such as 22 is placed upon the arbor 14 the pedal 64 may be pressed downwardly so that air will be admitted by

the valve 61 to the cylinder 41 to cause the piston F, rod 50 and cap 53 to move downwardly so that the cap will clamp the bushing 22 upon the flange 21 of the arbor. While the parts are in this position the pedal 37 may be pressed downwardly so that the valve 35 will permit air to enter the cylinder 19 and cause the pistons D and E to move upwardly. This will cause graphite to flow from the cylinder 12 through the axial, transverse and annular passages 16, 17 and 18 respectively to the grooves 70 in the bushing 22. Upon release of the pedal 37 the spring 40 will return the valve rocker 35 to exhaust position thereby relieving air pressure on the piston D. In this connection it will be noted that the action of the spring 40 and rocker 35 does not cause the pistons D and E to be lowered but permits them to remain in the position they just assumed. The pedal 64 may then be released whereupon the spring 67 causes the rocker 65 of the valve 61 to move in the opposite direction so that air will be admitted to the inlet 45 and will cause the piston F, rod 50 and cap 53 to be raised. Thus from the foregoing it will be apparent that repeated operation of the pedal 37 causes a step by step advancement upwardly of the pistons D and E until the cylinder 12 is emptied, as illustrated in Figure 1. Graphite must then be supplied through the inlet 13 through the cylinder 12 to cause the pistons D and E to be lowered to the position illustrated in Figure 1A, whereupon the successive step by step advancement upwardly may again take place by successive operations of the pedal 37. On the other hand, movement of the rocker 65 of the valve 61 in opposite directions causes air to be successively supplied to opposite ends of the cylinder 41 so that the cap 53 is positively lowered and raised.

What I claim as my invention is:

1. In a graphite machine, a cylinder for graphite, a bushing arbor adapted to receive graphite from the cylinder, an air cylinder, a piston in the air cylinder, and means in the cylinder for graphite operable by the piston to feed graphite from the cylinder to the arbor.
2. In a graphite machine, a pair of substantially aligned brackets, a bushing arbor carried by one of said brackets, a cap for the arbor, and means carried by the other of said brackets for actuating said cap.
3. In a graphite machine, a pair of vertically spaced brackets having substantially aligned tubular portions, a cylinder for graphite in one of said tubular portions, a bushing arbor associated with said cylinder and adapted to receive graphite therefrom, an air cylinder in the other tubular portion, a piston in the air cylinder, and a cap for the arbor movable by said piston.
4. In a graphite machine, a frame, a pair

of brackets projecting laterally from the frame, one of said brackets being adjustable on the frame, a bushing arbor carried by the other of said brackets, and a cap for the arbor carried by the adjustable bracket and movable relative thereto to and from the arbor.

5. In a graphite machine, a stationary arbor upon which a bushing is adapted to be sleeved and having means for conducting graphite to the interior of the bushing, and means for holding the bushing sleeved upon the arbor including a member mounted for longitudinal movement in substantial alignment with said arbor.

10. In a graphite machine, a stationary arbor of substantially cylindrical configuration upon which a bushing is adapted to be sleeved, and means for holding the bushing sleeved upon the arbor including a member mounted for longitudinal movement at one end of the arbor.

15. In a graphite machine, a stationary arbor upon which a bushing is adapted to be sleeved and having a passage for conducting graphite to the interior of the bushing, means for holding the bushing sleeved upon the arbor, including a member mounted for longitudinal movement adjacent the arbor, and means for supplying graphite to the passage aforesaid in the arbor including a member mounted for longitudinal movement in substantial alignment with said arbor.

20. In a graphite machine, a frame, a bracket carried by the frame, a cylinder for graphite carried by the bracket, an arbor for a bushing mounted on and having a passage for graphite in communication with said cylinder, a cylinder for compressed air suspended from the cylinder aforesaid, pistons operable within said cylinders, and a driving connection between said pistons.

25. In a graphite machine, a frame, a bracket carried by the frame, a cylinder for graphite carried by the bracket, an arbor for a bushing adjacent and having a passage for graphite in communication with said cylinder, a cylinder for compressed air adjacent the cylinder aforesaid, pistons operable within said cylinders, and a driving connection between said pistons.

30. In a graphite machine, an arbor upon which a bushing to be graphited is adapted to be sleeved and having a passage for conducting graphite to a bushing while sleeved thereon, said arbor being provided at one end with a seat for an end of the bushing, means enveloping the other end of the arbor and clamping the end aforesaid of the bushing against said seat, and means for forcing graphite through the passage while the bushing is clamped.

35. In a graphite machine, an arbor upon which a bushing is adapted to be sleeved, and means for holding a bushing sleeved upon

said arbor including means for partially enveloping the arbor.

40. In a graphite machine, an arbor upon which a bushing is adapted to be sleeved, and means for holding a bushing sleeved upon said arbor including means mounted for longitudinal movement adjacent to and adapted to partially envelope said arbor.

45. In a graphite machine, an arbor upon which a bushing is adapted to be sleeved, means for holding a bushing sleeved upon said arbor, and means operable while said bushing is held on the arbor for feeding graphite to the arbor, including a member mounted for longitudinal movement in substantial alignment with the arbor.

50. In a graphite machine, a stationary arbor upon which a bushing is adapted to be sleeved, including a rigid cylindrical member having a peripheral seat for an end of a bushing and having communicating axial and transverse passages for graphite.

In testimony whereof I affix my signature
OLIVER J. HEATH.
